Inventor:
Warren Fuhrmann,
By his Attorney W. H. Reich.

UNITED STATES PATENT OFFICE.

WARREN FUHRMANN, OF WESTFIELD, NEW JERSEY, ASSIGNOR, BY MESNE ASSIGNMENTS, TO WILKINSON BROTHERS AND COMPANY, INCORPORATED, OF NEW YORK, N. Y., A CORPORATION OF NEW YORK.

SIGNAL PRINTING MEANS FOR CALCULATORS.

1,313,177.

Specification of Letters Patent. Patented Aug. 12, 1919.

Application filed November 5, 1918. Serial No. 261,188.

To all whom it may concern:

Be it known that I, WARREN FUHRMANN, a citizen of the United States, residing at Westfield, in the county of Union and State 5 of New Jersey, have invented certain new and useful Improvements in Signal Printing Means for Calculators, of which the following is a specification.

This invention relates to calculators provided with means whereby special operations 10 are performed by the main operating member or handle upon previously depressing a special key, and which machines usually serve to print a character to indicate the 15 special operation of the machine. The object of the present invention is to provide special means for this purpose, wherein on depression of a special key a printing member is first positioned, and on further depression 20 of the key a previously cocked hammer is tripped to make the impression.

In the accompanying drawings illustrating one embodiment of my invention, Figure 1 is a side elevation of the parts in normal 25 position. Fig. 2 is a fragmentary elevation showing the first operation when the key is partly depressed. Fig. 3 shows the parts just after the impression has been made on full depression of the key. Fig. 4 shows 30 means for cocking the hammer. Fig. 5 shows the latter means in operation. Fig. 6 is a partial section on the line 6-6 of Fig. 1. Fig. 7 shows the latch. Fig. 8 shows the 35 hammer. Figs. 9 and 10 show the lever for cocking the hammer. Fig. 11 shows the arm for tripping the latch; and Fig. 12 shows the latch arm for the cocking lever.

This invention is in the nature of an improvement on the structure forming subject 40 matter of U. S. Patent No. 1,182,532. In such patent a bar is engaged by the special keys to be shifted rearwardly to set the type arm, and a second bar is swung on the other bar, to be later engaged by the same key 45 and rocked, to trip the cocked hammer. In the present invention this second bar is mounted independent of the other bar and is slidable, to be engaged by the depressed key at the latter portion of its movement, and advanced to trip the cocked hammer.

As shown in the drawings, on the side plate 1 is a bar 2 supported to slide back and forth, which bar is provided with cam faces

3, 4 and 5. Four special keys are shown 6, 55 7, 8 and 9 provided with pins 10, 11, 12, 13 respectively; which pins are adapted to engage the said cam faces on the bar 2, and force the bar rearward. A spring 14 on the arm 15 that supports the rear of the bar 2, 60 serves to move the bar forward when released from these keys.

A type carrier 16 is supported from an arm 17 hinged to the arm 15 whereby the rearward movement of the bar by the depression of a key will swing arms 15 and 17 65 to raise the carrier 16. The cam faces are so designed that each key will shift the bar a different distance, and hence bring one of the three lower type on the carrier opposite 70 the platen 18, according to which key is depressed. The carrier is normally positioned with the fourth type opposite a striking hammer 19, and the depression of one of the three keys will raise the carrier to bring 75 the corresponding type in position to be struck by this hammer. When the fourth key 9 is depressed the hammer is actuated but the carrier not moved.

The hammer 19, see Fig. 4, has an arm 20 80 arranged to engage a latch 21 that will hold the hammer in a cocked position under spring tension. The latch 21 is secured to a latch arm 22 that normally lies adjacent a trip arm 23, see Fig. 6, which arm is pivoted 85 on a bar 24, suitably mounted to slide rearward. This bar 24 is provided with four cam faces 25, 26, 27 and 28, arranged to be engaged by the said pins on the four keys, after the pins, or three of them have served 90 to engage the bar 2 and move it rearward. Each of the three keys 6, 7 or 8 when depressed will shift bar 24 to the rear, and the trip arm 23 will strike the latch arm 22, 95 whereby the latch 21 will move back to release the arm 20 of the hammer, and the latter is caused to strike the positioned type in the carrier. It will be understood that depression of either keys 6, 7 or 8 will first position the carrier 16 to bring one of the 100 three lower type to printing position, and thereupon the continued depression of this key will cause the bar 24 to move rearward and release the hammer 19 that will make the impression.

It is to be understood that this operation takes place at once on the full depression

- of the key, and previous to any movement of the main operating member of the machine, or advance of the usual pitman 29. This latter member is employed to reset 5 hammer 19 on its forward stroke. For this purpose a lever 30 is carried by an arm 31 fast on the main shaft 32, and when the pitman is moved forward by this shaft the lever 30 will be carried rearward, to swing 10 a lever 33 on the shaft 34 of the hammer 19. The lever 33 has an arm 35 that is bent to engage the hammer 19, and when the hammer has been tripped, see Fig. 4, this movement of these levers will swing the 15 hammer back to the position of Fig. 5, whereby the arm 20 of the hammer is caused to relatch on the latch 21. This hammer will remain latched during subsequent movements of the pitman and levers 30 and 20 33, that will not move the latch 21, until a key is depressed and the bar 24 moved rearward. In machines of this character the special keys are held depressed until the pitman moves forward and returns nearly 25 to normal position. This would interfere with the latching of the hammer because of the engagement of the latch arm 22 with the bar 24, by means of the trip arm 23 thereon. For this reason the trip arm 23 30 is pivoted on the bar 24. When the pitman moves forward a cam 36 will strike an ear 37 on the trip arm 23, and raise the bent end 38 of the trip arm above the projecting end 39 of the latch arm 22. See Fig. 6. 35 This will permit the latch arm and latch 21 to be returned to normal position by a spring 40; which is done just prior to the movement of the levers 30 and 33 to move the hammer back to cocking position, that 40 will permit the arm 20 to again engage the latch 21. As soon as the cam starts to return the trip arm 23 will return to normal position to engage the latch arm 22 when the special key is again depressed. 45 When released from the key pins, the bar 24 is retracted by a spring 42, extended between a pin 41 on the bar and a pin 43 on the side frame.

What I claim is:—

- 50 1. In a calculator, the combination with printing means and accumulating means, and special keys arranged to cause special operations of said means, of a type carrier provided with type corresponding with the 55 keys, a bar connected with the carrier, means connecting the bar and special keys whereby the bar is advanced by the keys for a different relative distance according to the key depressed, a signal printing member for causing said type in the carrier to print, a main operating member arranged to cock the signal printing member, and a strip arranged to release the cocked signal printing member to print, said strip being arranged 60 to be engaged by said special keys when de- 65

pressed after the key has advanced said bar to position the signal printing member to effect the impression of the positioned type carrier.

2. In a calculator, the combination with 70 printing means and accumulating means, and special keys arranged to cause special operations of said means, of a type carrier provided with type corresponding with the keys, a pin on each key, a bar connected 75 with the carrier and provided with cam shoulders arranged to be engaged by the key pins respectively whereby the bar is advanced for a different relative distance according to the key depressed, a signal printing member for causing said type in the carrier to print, a main operating member arranged to cock the signal printing member, and a strip arranged to release the cocked signal printing member to print, 80 said strip being arranged to be engaged by said key pins after the key has advanced said bar to position the signal printing member to effect the impression of the positioned type carrier. 90

3. In a calculator, the combination with 95 printing means and accumulating means, and special keys arranged to cause special operations of said means, of a type carrier provided with type corresponding with the keys, a pin on each key, a bar connected with the carrier and provided with cam shoulders arranged to be engaged by the key pins respectively whereby the bar is advanced for a different relative distance according to the 100 key depressed, a signal printing member for causing said type in the carrier to print, a main operating member arranged to cock the signal printing member, and a strip arranged to release the cocked signal 105 printing member to print, said strip being provided with cam shoulders arranged to be engaged by the said key pins after the key has advanced the bar to position the signal printing member, to effect the impression of the positioned type carrier. 110

4. In a calculator, the combination with 115 printing means and accumulating means, and special keys arranged to cause special operations of the said means, of a type carrier provided with type corresponding with the keys, means connected with the carrier and said keys whereby on depression of the keys the carrier is positively moved thereby to position the type according to the 120 key depressed, signal printing means for causing said type in the carrier to print, a main operating member arranged to cock the signal printing member, and a member engaged by said special keys when depressed 125 and arranged to release said cocked signal printing member after the key has caused the advance of the type carrier whereby to cause impression of the type in the positioned carrier. 130

5. In a calculator, the combination with printing means and accumulating means, and special keys arranged to cause special operations of said means, of a type carrier 30
5 provided with type corresponding with the keys, a bar connected with the carrier, means connecting the bar and special keys whereby the bar is advanced by the keys for a different relative distance according to the key 35
10 depressed, a signal printing member for causing said type in the carrier to print, a main operating member arranged to cock 40 the signal printing member, and a strip arranged to release the cocked signal printing member to print, said strip being arranged to be engaged by said special keys when depressed after the key has advanced said bar to position the signal printing member to effect the impression of the positioned type carrier, said signal printing means including a latch arm, a latch pivoted on said strip arranged to engage said arm when the strip is advanced by the key, whereby to effect the impression, and means 45
20 for swinging said latch after the printing member has been tripped and before release of the key. 50
25 55
6. In a calculator, the combination with printing means and accumulating means,

and special keys arranged to cause special operations of said means, of a type carrier provided with type corresponding with the keys, a pin on each key, a bar connected with the carrier and provided with cam shoulders arranged to be engaged by the key pins 35 respectively whereby the bar is advanced for a different relative distance according to the key depressed, a signal printing member for causing said type in the carrier to print, a main operating member arranged to cock 40 the signal printing member, and a slidable strip arranged to release the cocked signal printing member to print, said strip being provided with cam shoulders arranged to be engaged by the said key pins after the key has advanced the bar to position the signal printing member, to effect the impression of the positioned type carrier, said signal printing means including a latch arm, a latch pivoted on said strip arranged to engage said arm when the strip is advanced by the key, whereby to effect the impression, and means for swinging said latch after the printing member has been tripped and before release of the key. 55

Signed at New York city, N. Y. on Oct. 28", 1918. WARREN FUHRMANN.
